BY Victor J. Evans

ATTORNEY

WITNESSES

UNITED STATES PATENT OFFICE.

MILTON B. WRIGHT, OF SUMMIT, NEW JERSEY.

FOUNTAIN MARKING DEVICE.

Application filed December 10, 1923. Serial No. 679,833.

To all whom it may concern:

Be it known that I, MILTON B. WRIGHT, a citizen of the United States, residing at Summit, in the county of Union and State 5 of New Jersey, have invented new and useful Improvements in Fountain Marking Devices, of which the following is a specification.

This invention relates to fountain marking devices.

The principal object of the invention is the provision of a fountain marking device for use in writing upon boxes, crates or the like and which is so constructed that the 15 user may manipulate the same in a manner similar to that of an ordinary writing instrumentality.

Another object of the invention is to provide a fountain marking device wherein the 20 flow of ink from the reservoir is controlled by the pressure applied to the writing point of the device.

A further object of the invention is to provide a fountain marker wherein the 25 parts may be easily removed for cleaning purposes.

A still further object of the invention is to construct a fountain marker which is simple in construction, cheap of manufacture and highly efficient for the purpose intended.

With these and other objects in view, the invention resides in certain novel construction and combination and arrangement of parts, the essential features of which are 35 hereinafter fully described, are particularly pointed out in the appended claims, and are illustrated in the accompanying drawing, in which:—

Figure 1 is a vertical longitudinal section view through my invention.

Figure 2 is a horizontal sectional view on the line 2—2 of Figure 1.

Figure 3 is a collective view embodying 45 several of the parts of my invention.

Figure 4 is a view of my invention, showing the same partly in elevation and partly in vertical section.

Referring more particularly to the drawing, the reference numeral 10 designates my invention in its entirety which includes connectible parts 11, 12 and 13. The part 11 is in the nature of a hollow tube 14 which serves as a reservoir and has its outer end 50 closed by means of a removable cap 15 which permits access to the reservoir when

it is desired to fill the same with a writing fluid. The other end of the tube 14 is externally screw threaded as at 16 for co-acting engagement with the threads 17 formed in the walls of an annular recess 60 in the part 12. The part 12 serves as a connecting part between the part 11 and the part 13 and is provided with a central bore 18, the top walls of which are beveled 65 to provide a valve seat 19. The part 12 is reduced toward the bottom and is provided with a pair of diametrically opposed slots 20. A stem 21 extends through the bore 18 and has a valve head 22 removably supported from the upper end thereof. The valve head 22 co-acts with the seat 19 for a purpose to be presently described. The stem 21 is formed with opposed flat surfaces 23 which extend for a portion of its 75 length, and projecting therefrom in opposite directions are pins 24 for reception in the slots 20 of the part 12. The other or lower end of the stem 21 is threaded as at 26 for co-action with a threaded aperture 26' 80 formed in a metal clip 27 which is in turn connected with a stick of felt 28 by means of fingers 27'. The felt stick 28 has its free end pointed as at 29, which point serves as a writing point. A spring 30 is 85 interposed between the clip 27 and a shoulder formed on the part 12 so as to normally hold the valve head in engagement with the seat to prevent the flow of ink from the reservoir to the stick of felt 90 28. A sleeve 31 is sweated or otherwise secured to the part 12 and acts as a guard for preventing the flow of ink from contact with the fingers of the user, and a cap 32 is provided for telescopic engagement with the sleeve 31 when the marker is not in use so as to protect the felt stick 95 28.

In operation, the cap 32 is removed and the marker grasped in the manner of that used in grasping a pen or pencil. The pressure is then applied to the point 29 which causes an upward movement of the part 13 against the tension of the spring 30 and likewise unseats the valve head 22 to permit ink to flow downward by means of gravity 105 through the bore 18, it being understood that the bore is slightly larger in diameter than the stem 21. After passing through the bore, the ink then passes downward upon the felt stick 28 where it is absorbed down 110 to the point 29. When the ink has reached the point 29, it is of course understood that

the device is in readiness to be moved across a writing surface. It will be understood that pins 24 limit the upward movement of the valve head, and together with the flat surfaces 23 prevent rotation of the part 13.

From the construction and arrangement of the parts, the simplicity of the device will be readily understood, as the same may be 10 disassembled for cleaning purposes. In disassembling the parts, the tube 11 is first unscrewed from the part 12, after which the valve head 22 is removed from the end of the stem 21. The stem is then withdrawn 15 from the bore and carries the spring 30 therewith as one convolution of the spring is arranged between the pins 24. This will prevent the spring from suddenly flying off when disassembling these parts. If desired, 20 the felt stick may also be removed from the stem by unscrewing the same therefrom.

In Figures 1 and 4, there is shown a guard 33 which is carried by the tube 14 and extends downward as far as the termination of 25 the sleeve 31. The guard is spaced from the sleeve 31 to receive the cap 32 when the device is not in use. It will be seen that any ink which may accidentally accumulate 30 on the interior of the cap will not be brought into contact with any exterior surface which is intended to be grasped by the fingers of the user.

While I have described what I deem to be 35 the most desirable embodiment of my invention, it is obvious that many of the details may be varied without in any way departing from the spirit of my invention, and I therefore do not limit myself to the exact 40 details of construction herein set forth nor to anything less than the whole of my invention limited only by the appended claims.

What is claimed as new is:—

1. A fountain marker comprising a tubular member having one of its ends threaded, 45 a part provided with threads for co-action with the threads on said tubular member, a bore formed in said part, a valve seat arranged at the top of said bore, a stem extending through said bore, a valve head at 50 one end of said stem for co-action with said valve seat, a writing element removably supported from the other end by said stem, a spring positioned between said part and said writing element for normally holding said 55 valve head in engagement with said seat and whereby pressure on said writing ele-

ment will cause the unseating of said valve head for permitting the flow of liquid from said reservoir to said writing element.

2. A fountain marker comprising a tubular member having one of its ends threaded, 60 a part provided with threads for co-action with the threads on said tubular member, a bore formed in said part, a valve seat arranged at the top of said bore, a stem extending through said bore, a valve head at one end of said stem for co-action with said valve seat, means for preventing rotation of said stem, said means comprising pins carried by said stem and extending into 65 a slot in said part, a writing element removably supported from the other end by said stem, means for normally holding said valve head in engagement with said seat and whereby pressure on said writing element 70 will cause the unseating of said valve head for permitting the flow of liquid from said reservoir to said writing element.

3. A fountain marker comprising a tubular member having one of its ends threaded, 75 a part provided with threads for co-action with the threads on said tubular member, a bore formed in said part, a valve seat arranged at the top of said bore, a stem extending through said bore, a valve head removable at one end of said stem for co-action with said valve seat, means for preventing rotation of said stem, a writing element removably supported from the other end by said stem, means for normally holding said valve head in engagement with said seat and whereby pressure on said writing element 80 will cause the unseating of said valve head for permitting the flow of liquid from said reservoir to said writing element, 85 a sleeve carried by said part and depending midway between the length of said writing element, and a cap slidable over said sleeve.

4. A fountain marker including a reservoir, 90 a writing element, means for automatically permitting the flow of contents from said reservoir to said writing element, a sleeve for confining the flow to said writing element, a guard spaced from said 95 sleeve and encircling the same, and a cap for insertion in the space between said sleeve and said part.

In testimony whereof I have affixed my signature.

MILTON B. WRIGHT.
